Primary Examiner — Jonathan J Han(57) CLAIM

The ornamental design for a water shoe, as shown and described.

DESCRIPTION

FIG. 1 is a front, top and left side perspective view of a water shoe, showing my new design.

FIG. 2 is a left side view thereof.

FIG. 3 is a right side view thereof.

FIG. 4 is a front view thereof.

FIG. 5 is a rear view thereof.

FIG. 6 is a top view thereof.

FIG. 7 is a bottom view thereof; and,

FIG. 8 is a bottom perspective view thereof.

The broken lines are for the purpose of illustrating portions of the water shoe that form no part of the claimed design.

1 Claim, 8 Drawing Sheets(56)
